CLAIM

The ornamental design for a writing device, as shown and described.

DESCRIPTION

FIG. 1 is a perspective front view of a writing device showing our new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear perspective view thereof;

FIG. 8 is a second perspective front view thereof;

FIG. 9 is a rear view thereof;

FIG. 10 is a perspective front view of a writing device showing our new design;

FIG. 11 is a front view thereof;

FIG. 12 is a right side view thereof;

FIG. 13 is a left side view thereof;

FIG. 14 is a top view thereof;

FIG. 15 is a bottom view thereof;

FIG. 16 is a rear perspective view thereof;

FIG. 17 is a second perspective front view thereof; and,

FIG. 18 is a rear view thereof.

The broken line showing of the environmental structure of the writing device in FIGS. 1–9 is for illustrative purposes only and forms no part of the claimed design.
